UNITED STATES PATENT OFFICE.

JOHN ALFRED JACKSON AND PATRICK SWANSON, OF INVERCARGILL, NEW ZEALAND.

CARBURETOR.

Application filed September 18, 1920. Serial No. 411,102.

The object of the invention is to provide an apparatus whereby and wherein hydro-carbon fuel is mixed with air so as to provide a comparatively dry gaseous mixture 5 of a consistency variable at will for use in internal combustion engines.

With this object in view, we provide an apparatus whereby air induced into the apparatus is charged with vapour of hydro-carbon fuel in such a way that liquid particles of fuel are eliminated and the quantity 10 of vapour to air can be regulated.

The following is a description of our apparatus with reference to the accompanying 15 drawings, in which:—

Figure 1 is a sectional elevation of the apparatus, the part omitted being that of the float chamber unit.

Figure 2 is a plan view of the apparatus. 20 Figure 3 is a perspective view of the valve, regulating the admission of extra air to the secondary mixing chamber, and of the valve seat, and a portion of its spindle.

Figure 4 is a part perspective view of the 25 adjustable tube, showing the method of attaching selector and diffuser.

There is a vertically disposed well member 1, having a suitable communication 2 with the liquid fuel supply from the usual 30 float chamber 3, the arrangement being such that the fuel is maintained within the well at substantially a constant level 4. There is a pad 5 of absorbent material in the well 1, extending from the bottom 1^a to above 35 the petrol level 4. The well member 1 is partially partitioned by an adjustable apertured cover 6, disposed in the well 1 above petrol level, mainly for the purpose of protecting the absorbent material 5, and to 40 assist in directing the induced flow of air from the air passage 9 over the said material.

There is an adjustable vertical tube 7, internally in the form of a choke or Venturi tube, as indicated at 7^a, the said vertical tube forming a primary mixing chamber, the adjustable tube projects downwardly 45 through the secondary mixing chamber 8, in a guide aperture 8^a in the wall of the said chamber 8, and into an air passage 9; the adjustable tube is suspended concentrically over the well 1, the lower portion of the adjustable tube being in close proximity 50 to the absorbent material 5, and over the aperture 6^a in the cover 6. The adjustable

tube is smaller in diameter than the well member 1, and its lower end is provided with a hydro-carbon contact member and diffuser, which is preferably dome shaped and consists of finely meshed supporting material 7^c covered with suitable pervious absorbent material 7^b.

Ready means are provided for attaching and detaching the contact member for renewal purposes; the construction being 65 more clearly shown in the enlarged view, Figure 4, in which the adjustable tube is indicated at 7, the pervious material 7^b, and the wire gauze 7^c. The exterior 7^e of the lower end of the adjustable tube 7 is tapered, and above the taper for a short distance is threaded as at 7ⁱ, with which the thread 7^j on a detachable union member 7^k registers, the lower end 7^l of the said threaded union member being contracted in diameter, the reduced diameter of the interior surface 7^m thereof corresponds with the tapered bottom end of the adjustable tube 7, but is of greater diameter to form a space 7ⁿ, and the lower end of the internal constructed diameter part terminates in a flange 7° providing a seat 7^p for the pervious absorbent material 7^b and the gauze 7^c, the mouth of which is made to suit the taper on the lower end of the adjustable tube 7, and fit into the space 7ⁿ left between the said lower tapered end and contracted interior 80 diameter of the union member.

On screwing the detachable union member home, as indicated in Figure 4, the pervious absorbent material and gauze is retained in the position indicated in Figure 1. The adjustable tube is adjustable by means of the screw 7^r. The end 7^s of the said screw 7^r is secured to the top end of the adjustable tube 7 which projects therefrom upwards through a nut cap 8^c which is detachably fixed to the body 8^e of the secondary mixing chamber 8 as indicated at 8^p. The said nut cap is provided with a threaded 85 aperture to register with the screw 7^r.

Means are provided whereby the said screw 7^r may be screwed downwardly and in an upward direction to reduce or increase the area of approximation or contact between the lower end of the primary mixing chamber and the absorbent material in the fuel well.

The means referred to comprise a universal joint 7^t coupling a connecting rod 7^u 110

2
with the screw 7^R, the said connecting rod 7^U terminates in a knurled control 7^V secured to a dash-board (not shown) or the steering column (not shown) of a motor vehicle, so that greater or lesser contact or approximation may be made between the surfaces of the contact member and of the absorbent material in the well 1 above referred to. The adjustable tube 7 in that portion 7^D thereof above the point of affixation of the contact member is provided with suitable air inlets 7^P forming communication between the air passage 9 and the interior 7^F of the adjustable tube 7.

15 The adjustable tube in its upper portion is provided with suitable outlet apertures 7^G forming communication between the interior 7^F of the adjustable tube and the secondary mixing chamber 8.

20 The secondary mixing chamber 8 is provided with an automatic air valve, comprising a valve seat 10, having air inlet apertures 10^A, and valve 11 slidably mounted on a horizontal spindle 12. The said spindle 25 projects rearwards from the gas outlet 8^B across the main air inlet 18, into and through a nut 13 in the rear wall 18^A of the air inlet 18; the end 12^A of the spindle 12 is threaded to register with a threaded part of the nut 30 13, and is long enough to project so that the jamb nut 14 may be used to lock the unit in the desired position, the adjustment being made by turning the knurled head 15 attached to the end 12^A of the horizontal spindle 12.

35 The medium influencing the adjustment of the valve 11 comprises two springs 16 and 17, of different diameters, the larger one 16 is for the purpose of overcoming by its influence the smaller one 17 to create a greater or lesser resistance of the valve 11 against the suction due to the induction stroke of the engine. It will be observed that on turning the threaded projected end 12^A of the 40 spindle 12, as in the manner of screwing a bolt or stud home, the valve unit will project increasingly into the interior of the chamber 8, whereby the pressure of the springs will decrease and the resistance to the opening of the valve diminish. The 45 reverse operation of the spindle 12 increases the resistance of the valve, and thus the air admission under the suction of the engine can be regulated.

50 Having thus described our invention, what

we claim as new and desire to secure by Letters Patent is:—

1. A carburetor comprising a casing formed with an air inlet and with a partition dividing the casing into an upper and a lower air chamber, a well removably secured at the lowest point of the casing, means for admitting a liquid hydrocarbon to the well, a mass of absorbent material in the well and extended above the level of the hydrocarbon therein, a hollow member slidable in said partition in line with the well and adjustable from beyond the carburetor relative to the well, the lower end of the hollow member being of mesh material covered with an absorbent layer, that portion of the wall of the hollow member above the mesh material being formed with openings to establish communication between the interior of the member and the lower air chamber, the upper end of the hollow member being formed with openings to establish communication between the interior of said member and the upper air chamber.

2. A carburetor comprising a casing formed with an air inlet and with a partition dividing the casing into an upper and a lower air chamber, a well removably secured at the lowest point of the casing, means for admitting a liquid hydrocarbon to the well, a mass of absorbent material in the well and extended above the level of the hydrocarbon therein, a hollow member slidable in said partition in line with the well and adjustable from beyond the carburetor relative to the well, the lower end of the hollow member being of mesh material covered with an absorbent layer, that portion of the wall of the hollow member above the mesh material being formed with openings to establish communication between the interior of the member and the lower air chamber, the upper end of the hollow member being formed with openings to establish communication between the interior of said member and the upper air chamber, the interior of the hollow member being of minimum diameter intermediate said sets of openings and of gradually increasing diameter in both directions toward each respective set of openings.

In witness whereof we affix our signatures.

JOHN ALFRED JACKSON.
PATRICK SWANSON.
